APPARATUS FOR PHOTOGRAPHIC
CONTACT PRINTING

Lodewijk Evert van der Grinten, Venlo, Netherlands, assignor, by mesne assignments, to Chemische Fabriek L. van der Grinten N. V., Venlo, Netherlands, a corporation of the Netherlands

Application July 19, 1950, Serial No. 174,666

Claims priority, application Netherlands
July 21, 1949

16 Claims. (Cl. 95—77.5)

1

The invention relates to a type of photographic contact-printing apparatus comprising a panel of light-transmitting material curved in one direction and substantially straight in the other direction, i. e. linearly curved, having on its convex side, which may be termed a straight convex surface, a flexible applying apron for applying and pressing the material to be exposed onto the panel under tension, the said apron extending tangentially off the panel in the resting (i. e. feeding or loading) position of the apparatus and following the surface of the panel in the working position of the apparatus.

Exposure apparatus as thus far described is known.

A simple form of such apparatus is found in the so-called printing windows or panels. In such an apparatus the applying apron should be transparent. The operation of such apparatus is, however, not simple and the apparatus does not function faultlessly.

A more complete form of such a contact printing apparatus effects exposure from the concave side of the panel. In this latter case the panel is rotatable about a central axis and the apron is wound and unwound on the panel by this rotation.

All these known forms of apparatus have the disadvantage that the original to be copied, after having been applied on the apron together with the copying material in the resting (i. e. feeding) position of the apparatus, has then to be set moving together with the apron. This may involve difficulties especially when the original or the copying material forms part of a larger aggregate (for example, when it is a page from a book), so that this larger aggregate, properly supported, also has to undergo the whole of this movement. During the movement the original gradually disappears from sight. Thus, if the copy material shifts or crumples during the movement, this cannot be seen and such shifting or crumpling cannot be controlled.

It is an object of this invention to provide apparatus in which the movement of the copy material is eliminated or reduced to a minimum. Other important objects of the invention will be apparent from the following description.

According to the present invention photographic contact-printing apparatus, comprises a linearly curved exposure panel of light-transmitting material adapted to be illuminated from the concave side thereof, an apron adapted to be laid close to the convex side of said panel following the contour of the panel and to sandwich

between itself and the panel a sheet of light-sensitive material and an original sheet to be copied, means for rolling the panel to and fro between a resting position in which the panel and the apron are apart and the apron lies tangentially to the panel and a working position in which the apron follows the contour of the panel. According to a further feature of the invention, the apparatus comprises means for holding the apron under tension in a direction perpendicular to the generating lines of the panel.

Preferably one end of the apron is attached to the panel, or to the casing holding the panel, along a generating line of the panel and the other end terminates at an edge which is thin and flat and is parallel to the generating lines of the panel. Preferably the said terminal edge is anchored in a fixed position within the apparatus.

The invention will now be described with reference to the accompanying drawings which illustrate preferred forms of the apparatus of the invention.

Figs. 1 and 2 illustrate, in the resting and working positions respectively, an apparatus for making copies on a table.

Figs. 3 and 4 similarly illustrate a simple apparatus for copying pages from books.

Figs. 5 and 6 illustrate, again in the resting and working positions respectively, an apparatus with a stationary source of light and devices for screening the light in the resting position.

Figs. 7 and 8 illustrate, in the resting and working positions respectively, an apparatus with a cylindrical panel capable of rolling to and fro.

Figs. 9 and 10 illustrate, in the resting and working positions respectively, apparatus in which a source of light moves together with the panel and is screened in the resting position.

Referring to Figs. 1 and 2, the apparatus comprises a lamp 1, a reflector casing 2, a curved panel 3, an applying apron 4, a table 5 on which the free end of the apron is fastened at 15, the other end of the said apron being fastened at 7 to the panel or to the exposure casing. Two flexible, elastic, tightened straining tapes 6, provided on either side of the apron, are secured to the panel or casing at 27, pass along at the outside of the curved panel 3 or the corresponding part of the exposure casing 2 towards the back of the table 5 where they are secured at 28. These flexible elastic, tightened straining members 6 thus cross the apron 4 and run onto and off the curved panel 3 in the reverse direction to the apron itself. This device keeps the apron 4 under constant tension, on the one hand via table

2

5 and on the other hand via the panel system. The apparatus, as illustrated in all the figures, is operated from the left.

A device for limiting the final position with respect to the rolling movements of the panel comprises the link 16, which is pivotally mounted on the table 5 at 17 and which has a slot in which the pin 18 mounted on the casing 2 is limited in its freedom of movement. The weight 19 illustrates diagrammatically that the centre of gravity of the panel together with all the parts joining in its movement is so disposed that it is stable only in the feeding position (Fig. 1) or the working position (Fig. 2) while being unstable in the intermediate positions.

In the resting (i. e. loading or feeding) position according to Fig. 1, material for contact printing may be placed onto the apron 4, and when the panel and the exposure casing are transferred by means of the handle 9 from the position of Fig. 1 to that of Fig. 2 and kept in the latter position, all the conditions required for contact-printing are fulfilled.

From the above description it is clear that apparatus according to the invention may be very simply constructed and very easily operated.

In a particularly satisfactory form of the invention the free end of the apron forms a terminal edge engaged by tension members, said edge being parallel to the generating lines of the panel, being flat and thin, or at least thinning towards the end, and extending freely, unobstructed by the tension members acting upon the said edge. Such an apparatus is illustrated in Fig. 3.

Referring to Fig. 3, the apparatus comprises a source of light 1, a reflector casing 2a, a curved panel 3a, an apron 4a and a table 5a. The apron is fastened to the panel or casing at 7a. A plate 10 lies below the apron 4a and is connected at one end to the terminal edge 6 of the apron. The flexible, but non-elastic straining tapes 8a, provided on either side of the apron, are secured at 27 to the panel or casing and pass along the outside of the curved panel 3a or the corresponding part of the casing 2a towards the edge of the plate 10 opposite the edge of the said plate connected to the terminal edge 6. They engage the said edge by passing over the two pulleys 29 provided on the supports 28 and connect with the springs 31, which are anchored to supports 32. The straining members 8a thus cross the apron 4a and run onto and off the curved panel 3a in the reverse direction to the apron itself. The apron 4a is thus kept under tension via the plate 10 and on the other hand via the panel system, in a manner analogous to that of Figs. 1 and 2. The exposure casing has a handle 9a, while the plate 10 is supported by the supports 11 and connected to table 5a. The supports leave the bottom surface of the plate 10 substantially free. Near the fastening 6 the apron and the plate 10 form a flat thin edge.

The spring 31 pulls, by means of tapes 8a passing the roller 33, the edge 27 in Fig. 3 to the right and somewhat in a downward direction. The force exerted therefore is substantially directed to the right and is transmitted through the curved panel to the edge 7a where it acts (vide Fig. 3) in a horizontal direction and to the right. At the edge 7a the force just referred to is transmitted to the applying apron 4a with the result that this apron is also pulled to the right, which means that there is a tension in the apron pulling the edge 6 also to the right. At this place 6 however the plate 10 engages the

apron 4a and prevents this edge from being moved to the right. The plate 10 therefore of course has to exert a reaction force to the left.

The apparatus of Fig. 3 is suitable for making copies, for example, reflex copies, from pages of books. The way in which the apparatus is used for this purpose is illustrated in Fig. 3. As there shown the page 12 of the book to be copied is laid over the apron 4a, while the photosensitive material 13 on which a reflex copy of this page is to be produced is laid over the page 12. The apparatus is rolled from the resting position to the working position in the same way as described in relation to Figs. 1 and 2, thus reaching the working position of Fig. 4. The latter figure also illustrates that the apron 4a and the curved panel 3a are interconnected in such a relative position that in the working position (in which the apron is wound onto the panel) a free edge 14 of the panel extending on one of the generating lines of the panel registers with the terminal edge 6 of the apron, i. e. it meets the said terminal edge 6 as accurately as possible when the working position is reached. As is demonstrated by the book illustrated diagrammatically in Fig. 4, this disposition presents especial advantages, if it is desired to photoprint the page right up to the fold or spine of the book.

In Fig. 4 the page 12 and the photo-sensitive material 13 have, of course, become invisible, because the apron 4a is pressed onto the curved panel 3a.

In the apparatus of Figures 1-4 the source of light moves with the panel assembly during the passage from the resting position to the working position and vice versa. Figs. 5 and 6 illustrate diagrammatically that this is, of course, not necessarily the case and that the source of light may, for example, also be stationary. In certain circumstances this is advantageous since the provision of a simple screen 26 attached to the panel prevents any undesirable light from the source of light from passing through the curved panel to the apron in the resting position (Fig. 5), while in the case of lamps sensitive to shock it is advantageous if they are not moved.

The stiff plate 10, illustrated in Figs. 3-6, which is substantially parallel to the surface of the freely extending end of the apron, but which may also have a slight curvature (for example, with the convex side turned upwards) provided its generating lines are parallel to those of the curved panel, and which ends with one of its edges in the flat and thin terminal edge of the apron, constitutes a particularly efficient tension device for a flat, thin and free terminal edge.

In the apparatus of this invention the pressure (copying pressure) required for good contact is produced, in a manner known per se, by the tension of the apron in co-operation with the convex side of the panel. With a given tension this copying pressure increases as the curvature of the panel increases, in other words as its radius decreases. In Figs. 7 and 8 an apparatus is illustrated in the resting position and working position respectively, in which the curved panel is a complete cylinder 3c having a small radius. This apparatus operates in essentially the same way as the apparatus according to Figs. 1 and 2. The tension device in these two figures is as follows: at 7c the apron 4c is extended by means of the two flexible and elastic straining tapes 8c. These tapes are provided on either side

beyond the width of the apron 4c and are looped about the curved panel together with this apron, as is clearly visible in Fig. 7, the apron passing between the two straining members. The elastic tapes 8c are fastened to the table 5c and at 28c.

When the apparatus according to the invention is combined with a source of light fastened to the concave side of the curved panel, in such a manner that this source of light moves with the panel, the peculiar features of the apparatus according to the invention may be simply turned to account as illustrated in Figs. 9 and 10 in order to screen the light in the feeding position.

In the embodiment of Figs. 9 and 10, the source of light 1d is partially surrounded by a screen 21, which may act as a reflector at the same time. It is rotatable in the casing 20, and during its rotation the source of light 1d remains in the centre. The screen 21 carries a lever 22 disposed outside the casing, having a pivot point 23 with which the rod 24 engages. The rod 24 pivots about a fixed point 25 on table 5d.

In the working position (Fig. 10) the opening of the screen 21 is directed towards the curved panel. During the movement from the working position to the resting position (Fig. 9) the rod 24 keeps the screen 21 in substantially the same direction via the lever 22, or at least substantially the same direction is attained again when the resting position has been completely reached. In the resting position the rays of the source of light cannot reach the panel 3. When the movement is reversed the screen 21 will return to the position shown in Fig. 10 and its opening will again be directed towards the panel 3.

What I claim is:

1. In a contact photoprinting apparatus, the combination of a support providing an elongated trackway for a rolling exposure member, an exposure member comprising a cylindrically curved light-pervious panel defining only part of a cylinder and rollable bodily on said trackway to move said surface to and fro along a path tangential to said surface with a rocking motion relative to the support, said trackway extending along said path, a flexible apron held to said panel surface and extending along it and tangentially from it to a terminal portion, and means anchoring said terminal portion to said support so as to prevent relative movement thereof longitudinally of the apron, so that rolling the panel away from said terminal portion exposes part of the apron to receive original and light-sensitive sheets for exposure and so that sheets placed over the exposed apron may be brought into close contact with the panel by rolling it over them toward said terminal portion.

2. An apparatus as described in claim 1, the apron being attached to the exposure member near and across an end of the panel surface remote from said terminal portion.

3. In a contact photoprinting apparatus, the combination of a support providing an elongated trackway for a rolling exposure member, an exposure member comprising an arcuate light-pervious panel having an outer surface convex in one direction and straight in the transverse direction, said exposure member being supported and rockable bodily on said trackway to move said surface to and fro relative to the support in a path tangential to said surface, said trackway extending along said path, a flexible apron held to said panel surface and extending along it and tangentially from it to a terminal portion, and means anchoring said terminal portion to said

support so as to prevent relative movement thereof longitudinally of the apron, so that rocking the panel away from said terminal portion exposes part of the apron to receive original and light-sensitive sheets for exposure and so that sheets placed over the exposed apron may be brought into close contact with the panel by

5 rocking it over them toward said terminal portion, said terminal portion of the apron having a 10 terminal edge substantially parallel to generating lines of said panel surface, and said panel surface having at one end a free edge substantially coinciding with said terminal edge when the panel is rocked fully toward the latter.

15 4. In a contact photoprinting apparatus, the combination of a support presenting a substantially flat working surface, an exposure member thereover comprising a curved light-pervious panel having an outer surface convex in one direction and straight in the transverse direction, said exposure member being supported by said panel surface bearing upon said working surface and being rollable bodily to and fro over the latter in a path tangential to said panel surface, a flexible 20 apron held to said panel surface and extending along it and tangentially from it over the working surface to a terminal portion, and means anchoring said terminal portion to said support so as to prevent relative movement thereof longitudinally of the apron, so that rolling the panel away from said terminal portion spreads the apron over the working surface to receive original and light sensitive sheets for exposure and so that sheets placed over the spread apron may 25 be brought into close contact with the panel by rolling it over them toward said terminal portion.

30 5. In a contact photoprinting apparatus, the combination of a support presenting a substantially flat working surface, an exposure member thereover comprising a curved light-pervious panel having an outer surface convex in one direction and straight in the transverse direction, said exposure member being supported by said panel surface bearing upon said working surface and being rollable bodily to and fro over the latter in a path tangential to said panel surface, a flexible apron held to said panel surface and extending along it and tangentially from it over the working surface to a terminal portion, and means anchoring said terminal portion to 35 said support so as to prevent relative movement thereof longitudinally of the apron, so that rolling the panel away from said terminal portion spreads the apron over the working surface to receive original and light sensitive sheets for exposure and so that sheets placed over the spread apron may be brought into close contact with the panel by rolling it over them toward said terminal portion.

40 6. In a contact photoprinting apparatus, the combination of a support presenting a substantially flat working surface, an exposure member thereon comprising a cylindrically curved light-pervious panel defining less than half a cylinder, said panel being supported on its convex surface by said working surface and being rockable bodily over the latter between a feeding position in which its backward end approaches said working surface and an exposing position in which its forward end approaches said working surface, a flexible apron held to the backward end of the panel and extending along and tan-

gentially from its convex surface over said working surface to a terminal portion, means anchoring said terminal portion to said support so as to prevent relative movement thereof longitudinally of the apron, and tensioning means holding said apron in a stretched condition comprising spaced elongated flexible members held to the forward end of the panel and extending along and tangentially to its convex surface at either side of the apron to terminal portions held to a backward part of said support.

7. An apparatus as described in claim 6, said flexible tensioning members comprising stretched elastic bands.

8. An apparatus as described in claim 6, said flexible tensioning members comprising substantially inelastic bands and tensioning springs mounted on the support.

9. In a contact photo-printing apparatus, the combination of an exposure member comprising a light-pervious panel of which the outer surface is convex in one direction and straight in the transverse direction, a support providing a trackway extending along a path tangential to said surface, said exposure member being supported and rollable bodily to and fro on said trackway so as to roll said surface along a path tangential to said surface, a flexible apron held to said member and arranged to extend over said surface and tangentially from it to a terminal portion of the apron, said terminal portion being anchored to a part of said support so as to prevent movement of said terminal portion longitudinally of the apron, the rolling of said member away from said terminal portion uncovering said apron so that sheet material may be placed on the apron for exposure, and sheet material so placed being wrapped against said surface by the rolling of said member toward said terminal portion.

10. In a contact photo-printing apparatus, the combination of an exposure member comprising a light-pervious panel of which the outer surface is convex in one direction and straight in the transverse direction, a support providing a trackway extending along a path tangential to said surface, said exposure member being supported and rollable bodily to and fro on said trackway so as to roll said surface along a path tangential to said surface, a flexible apron held to said member and arranged to extend over said surface and tangentially from it to a terminal portion of the apron, said terminal portion being anchored to a part of said support so as to prevent movement of said terminal portion longitudinally of the apron, the rolling of said member away from said terminal portion uncovering said apron for exposure, and sheet material so placed being wrapped against said surface by the rolling of said member toward said terminal portion, there being a thin stiff transverse edge at the end of said terminal portion, and means holding said edge substantially parallel to generating lines of said surface and in a position where it protrudes unobstructed so as to be inserted into the fold of a book when said member is rolled away from said terminal portion.

11. In a contact photo-printing apparatus, the combination of an exposure member comprising a light-pervious panel of which the outer surface is convex in one direction and straight in the transverse direction, a support providing a trackway extending along a path tangential to said surface, said exposure member being supported and rollable bodily to and fro on said trackway so as to roll said surface along a path tangential

to said surface, a flexible apron held to said member and arranged to extend over said surface and tangentially from it to a terminal portion of the apron, said terminal portion being anchored to

5 a part of said support so as to prevent movement of said terminal portion longitudinally of the apron, the rolling of said member away from said terminal portion uncovering said apron so that sheet material may be placed on the apron for exposure, and sheet material so placed being wrapped against said surface by the rolling of said member toward said terminal portion, and means for applying to said panel a tension acting in a direction opposite to the direction of extension of the apron from said panel surface so as to keep the apron in a stretched condition.

12. In a contact photo-printing apparatus, the combination of an exposure member comprising a light-pervious panel of which the outer surface is convex in one direction and straight in the transverse direction, a support providing a trackway extending along a path tangential to said surface, said exposure member being supported and rollable bodily to and fro on said trackway so as to roll said surface along a path tangential to said surface, a flexible apron held to said member and arranged to extend over said surface and tangentially from it to a terminal portion of the apron, said terminal portion being anchored to a part of said support so as to prevent movement of said terminal portion longitudinally of the apron, the rolling of said member away from said terminal portion uncovering said apron so that sheet material may be placed on the apron for exposure, and sheet material so placed being wrapped against said surface by the rolling of said member toward said terminal portion, and means for applying to said panel a tension acting in a direction opposite to the direction of extension of the apron from said panel surface so as to keep the apron in a stretched condition, said tension applying means including spaced elongated flexible members located on either side of the apron, held to said surface and extending tangentially from said surface in said opposite direction to a part of said support remote from said terminal portion, said flexible members crossing the apron near the location where the apron leaves said surface.

13. An apparatus as described in claim 12, said apron and said flexible members having interconnected end portions and forming a continuous band looped about said panel.

14. In a contact photo-printing apparatus, the combination of an exposure member comprising a light-pervious panel of which the outer surface is convex in one direction and straight in the transverse direction, a support providing a trackway extending along a path tangential to said surface, said exposure member being supported and rollable bodily to and fro on said trackway so as to roll said surface along a path tangential to said surface, a flexible apron held to said member and arranged to extend over said surface and tangentially from it to a terminal portion of the apron, said terminal portion being anchored to a part of said support so as to prevent movement of said terminal portion longitudinally of the apron, the rolling of said member away from said terminal portion uncovering said apron so that sheet material may be placed on the apron for exposure, and sheet material so placed being wrapped against said surface by the rolling of said member toward said terminal portion, and means lying in the path of movement of abut-

ment means on said exposure member to limit the rolling movement of the panel in each direction of such rolling movement.

15. In a contact photo-printing apparatus, the combination of an exposure member comprising a light-pervious panel of which the outer surface is convex in one direction and straight in the transverse direction, a support providing a trackway extending along a path tangential to said surface, said exposure member being supported and rollable bodily to and fro on said trackway so as to roll said surface along a path tangential to said surface, a flexible apron held to said member and arranged to extend over said surface and tangentially from it to a terminal portion of the 15 apron, said terminal portion being anchored to a part of said support so as to prevent movement of said terminal portion longitudinally of the apron, the rolling of said member away from said terminal portion uncovering said apron so that sheet material may be placed on the apron for exposure, and sheet material so placed being wrapped against said surface by the rolling of said member toward said terminal portion, a light source at the concave side of said panel, a 25 light shield movable to and from a position blocking the path of light emission from said source to said panel, and means responsive to the rolling movement of said exposure member for moving said shield to and from said light blocking position, respectively, as said member is rolled away from and toward said terminal portion.

16. In a contact photo-printing apparatus, the combination of an exposure member comprising a light-pervious panel of which the outer surface is convex in one direction and straight in the transverse direction, a support providing a trackway extending along a path tangential to said surface, said exposure member being supported and rollable bodily to and fro on said trackway so as to roll said surface along a path tangential 35

to said surface, a flexible apron held to said member and arranged to extend over said surface and tangentially from it to a terminal portion of the apron, said terminal portion being anchored to a 5 part of said support so as to prevent movement of said terminal portion longitudinally of the apron, the rolling of said member away from said terminal portion to a feeding position uncovering said apron so that sheet material may be placed on the apron for exposure, and sheet material so placed being wrapped against said surface by the rolling of said member toward said terminal portion to a working position, a light source at the concave side of said panel, a tubular light shield rotatably mounted in said exposure member and partially surrounding the light source, said shield having an opening for the passage of light and having a reflective inner surface, and means for rotating said shield about said source so as to block the path of light between said source and said panel when said exposure member is in feeding position and to dispose said opening therebetween when said member is in working position.
